UNITED STATES PATENT OFFICE.

RUDOLF PRACHT, OF BRESLAU, GERMANY.

TELESCOPIC BOX.

1,069,723.

Specification of Letters Patent.

Patented Aug. 12, 1913.

Application filed February 26, 1912. Serial No. 680,048.

To all whom it may concern:

Be it known that I, RUDOLF PRACHT, a subject of the Emperor of Germany, residing at Breslau, in Germany, have invented 5 a certain new and useful Telescopic Box, of which the following is a specification.

This invention relates to telescopic boxes.

The invention consists in the combination and arrangement of parts hereinafter described and particularly pointed out in the 10 claims.

In the accompanying drawing, Figure 1 shows in perspective view by way of example a construction of a box with a lid which 15 can be turned upward on the bottom part, while Fig. 2 is a vertical section through the box. Fig. 3 is a view similar to Fig. 2 of the rear part of the box, showing the lid as swung open.

20 The lid 1 is hinged to the bottom part 2 by means of hinges 3 and carries, near the front bottom edge, lock parts 4 the complementary parts 5 of the lock being mounted on the bottom part of the box. The hinges 25 3 and the lock parts 5 project through slots 17 in the front and back wall respectively of the bottom part of the trunk, into the interior of the same, and are rigidly connected to support members 6, 7, 8 made of 30 the usual U-shape. The branches 6, 8 are vertically adjustable in guides 9 mounted inside the box. For securing them in position, the branches 6, 8 are provided with holes 10 in which can engage pins 11 secured 35 to the wall of the bottom box half. The holes are preferably located above the lock and hinge parts, so that these do not sustain any pressure which may be exerted on the box lid.

40 It will be seen that by vertical adjustment of the support members the lock parts 5 and the hinges 3 are shifted together, so that the box can be closed whatever the position given to the lid. To allow the lid 45 to be conveniently opened and closed in any position, its front edge 1' is suitably curved. If this were not the case, the lid could be only lifted off, and not turned up. In the box illustrated, an additional means for securing the lid in the closed position is provided, consisting in a hook 12 projecting from the inner wall of the lid edge 1' carrying the lock parts 4, which hook, when the lid is closed, engages under the cross piece 50 55 7 of the front support member, so that the lid can be swung upward only after the

hook has been disengaged from the cross-piece. This disengagement is provided for by the mounting of hook 12 on a bracket 13 movable outwardly, the bottom part 14 of which bracket forms a latch for a lock 15 arranged below it. In order to prevent unauthorized forcing back of the front wall of the bottom box half, and consequent disengagement of the hook 12 from the cross-piece 7, the side of the lid is provided with a projection 18 with which the support member engages when the lid is closed.

To allow the lid, when open, to remain in a position swung backward beyond the vertical, it is provided in the usual manner with retaining bands 16 secured to the top part of the box. In the present case the retaining bands are connected directly to the rear support members 7 so that on vertical adjustment of the rear support, both the hinges 3 and the bands are shifted in accordance with the new position of the lid, the relative position of the bands and the lid and therefore the action of the former 75 being thus preserved in all adjustments of the lid.

The operation of the telescopic box will be clear from the foregoing description. In order to vary the capacity of the box it 80 is merely necessary to raise or lower the back and front support members. The lock parts 5, hinges 3, and bands 16, are thereby shifted, to correspond to the new lid position whereupon the box is again ready for 85 use.

What I claim is:

1. In an adjustable packing receptacle the combination of a lower portion, an upper portion, hinges hinging the upper portion to the lower portion, locking means for the upper portion comprising complementary members one of which is carried by the upper portion, vertically-adjustable support members carried by the front and rear walls of the lower portion of the receptacle and to which support members the hinges and the other of the complementary lock members are connected and adjustable simultaneously therewith, each of said support members being of U-shape, means carried by the upper portion of the receptacle and adapted to engage beneath the connecting cross-piece of the front support member when the upper portion is closed, and means for securing the support members in adjusted positions.
2. In an adjustable packing receptacle the

combination of a lower portion, an upper portion, hinges hinging the upper portion to the lower portion, locking means for the upper portion comprising complementary members one of which is carried by the upper portion, vertically - adjustable support members carried by the front and rear walls of the lower portion of the receptacle and to which support members the hinges and the other of the complementary lock members are connected and adjustable simultaneously therewith, said support members being of U-shape and the legs of which are provided with apertures, pins carried by the lower portion of the receptacle and adapted to engage said apertures above the line of the hinges and the lock members, for the purpose specified.

3. In an adjustable packing receptacle the combination of a lower portion, an upper portion, hinges hinging the upper portion to the lower portion, locking means for the upper portion comprising complementary members one of which is carried by the upper portion, vertically - adjustable support members carried by the front and rear walls of the lower portion of the receptacle and to which support members the hinges and the other of the complementary lock members are connected and adjustable simultaneously therewith, each of said support members being of U-shape, means carried by the upper portion of the receptacle and adapted to engage beneath the connecting cross-piece of the front support member when the upper portion is closed, means carried by the upper portion of the receptacle and adapted to hook onto the connecting cross-piece of the back support member when the box is open, and means for securing the support members in adjusted positions.

4. In an adjustable packing receptacle the combination of a lower portion, an upper portion, hinges hinging the upper portion to the lower portion, locking means for the upper portion comprising complementary members one of which is carried by the upper portion, vertically - adjustable support members carried by the front and rear walls of the lower portion of the receptacle and to which support members the hinges and the other of the complementary lock members are connected and adjustable simultaneously therewith, each of said support members being of U-shape, means carried by the upper portion of the receptacle and adapted to engage beneath the connecting cross-piece of the front support member when the upper portion is closed, means carried by the upper portion of the receptacle and adapted to hook onto the connecting cross-piece of the back support member when the box is open, and means for securing the support members in adjusted positions.

portion of the receptacle and adapted to engage behind the front support member when the upper portion is closed, and means for securing the support members in adjusted positions.

4. In an adjustable packing receptacle the combination of a lower portion, an upper portion, hinges hinging the upper portion to the lower portion, locking means for the upper portion comprising complementary members one of which is carried by the upper portion, vertically - adjustable support members carried by the front and rear walls of the lower portion of the receptacle and to which support members the hinges and the other of the complementary lock members are connected and adjustable simultaneously therewith, each of said support members being of U-shape, means carried by the upper portion of the receptacle and adapted to engage beneath the connecting cross-piece of the front support member when the upper portion is closed, means carried by the upper portion of the receptacle and adapted to hook onto the connecting cross-piece of the back support member when the box is open, and means for securing the support members in adjusted positions.

In testimony whereof I have signed my name to this specification in the presence of two subscribing witnesses.

RUDOLF PRACHT.
